(57) **CLAIM**

The ornamental design for a power strip, as shown and described.

DESCRIPTION

FIG. 1 is a perspective view of a power strip according to an embodiment of the present design.

FIG. 2 is a top plan view of the power strip of FIG. 1.

FIG. 3 is a bottom plan view of the power strip of FIG. 1.

FIG. 4 is a back side elevational view of the power strip of FIG. 1.

FIG. 5 is a front side elevational view of the power strip of FIG. 1.

FIG. 6 is a right side elevational view of the power strip of FIG. 1; and,

FIG. 7 is a left side elevational view of the power strip of FIG. 1.

The broken lines shown in FIGS. 1 through 7 illustrate portions of the power strip that form no part of the claimed design.
